(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

1. Display screen or portion thereof with graphical user interface

1 : Front

Reproduction 1 is a front view of a display screen or portion thereof with graphical user interface showing our new design; the outer perimeter shown in a pair of broken lines in the reproduction illustrates a display screen or portion thereof and forms no part of the claimed design; the dot-dash broken lines define boundaries of the claimed design and form no part thereof.
